UNITED STATES PATENT OFFICE

137,669

DESIGN FOR A TRUSS BRACKET FOR BICYCLES

Frank W. Schwinn, Chicago, Ill.

Application November 10, 1943, Serial No. 111,642

Term of patent 14 years

(Cl. D90—9)

To all whom it may concern:

Be it known that I, Frank W. Schwinn, a citizen of the United States, residing at Chicago, in the county of Cook and State of Illinois, have invented a new, original, and ornamental Design for a Truss Bracket for Bicycles, of which the following is a specification, reference being had to the accompanying drawing, forming part thereof.

Fig. 1 is a side elevational view of a truss bracket for bicycles embodying my new design;

Fig. 2 is a front elevational view of the truss bracket;

Fig. 3 is a front and top view of the bracket in perspective;

Fig. 4 is a cross sectional view, taken on the plane of the line 4—4 of Fig. 3, looking in the direction of the arrows.

I claim:

The ornamental design for a truss bracket for bicycles, substantially as shown.

FRANK W. SCHWINN.
